United States Patent Office

Des. 193,665
Patented Sept. 25, 1962

193,665

ARTIST'S EASEL

Alexander Rosenfeld, 3345 Blair Drive,
Los Angeles, Calif.

Filed Mar. 19, 1962, Ser. No. 69,329

Term of patent 14 years

(Cl. D29—20)

FIG. 3

FIG. 1 is a front perspective view of an artist's easel embodying my new design;

FIG. 2 is a side elevation of the same, and

FIG. 3 is a rear elevational view of the same.

I claim:

The ornamental design for an artist's easel, substantially as shown.
